Primary Examiner — Kevin K Rudzinski*Assistant Examiner* — James P McKane(74) *Attorney, Agent, or Firm* — Tutunjian & Bitetto, P.C.(57) **CLAIM**

The ornamental design for a sunhat with opening, as shown and described.

DESCRIPTION

FIG. 1 is a perspective view showing my new design for a sunhat with opening;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear view of the sunhat with opening in an alternate position.

The shade lines on the surfaces of the sunhat with opening define the contours of the hat and do not reflect a particular surface ornamentation or material.

The broken lines in the drawing figures depict portions and a boundary line of the sunhat with opening which form no part of the claimed design.
